Anna G. Granowitz, New York, N. Y.

Application August 15, 1950, Serial No. 11,770

Term of patent 14 years

(Cl. D80—9)

To all whom it may concern:

Be it known that I, Anna G. Granowitz, a citizen of the United States of America, residing in New York city, county of New York, and State of New York, have invented a new, original, and ornamental Design for a Cup and Saucer Display Stand, of which the following is a specification, reference being had to the accompanying drawing, forming part thereof, wherein:

I claim:

The ornamental design for a cup and saucer display stand, substantially as shown.

ANNA G. GRANOWITZ.
